UNITED STATES PATENT OFFICE

ARTHUR CHARLES CAVENDISH LIARDET, OF LONDON, ENGLAND.

NON-REFILLABLE BOTTLE.

SPECIFICATION forming part of Letters Patent No. 665,023, dated January 1, 1901.

Application filed February 6, 1900. Serial No. 4,245. (No model.)

To all whom it may concern:

Be it known that I, ARTHUR CHARLES CAVENDISH LIARDET, gentleman, a subject of the Queen of Great Britain, residing at 31 Upper Bedford Place, London, England, have invented certain new and useful Improvements in Non-Refillable Bottles, of which the following is a specification.

This invention relates to non-refillable bottles and similar liquid-containing vessels, and has special reference to the class of such bottles in which a float-valve and a plug or baffle in the neck of the bottle are employed.

According to my invention I construct the float-valve of a hollow hermetically-sealed body with a pointed, conical, or similarly-shaped head, so that when the liquid contents of the bottle are being poured out the incoming air will not be liable to cause the said float-valve to return to its seating. Furthermore, the pointed shape of the said valve also insures that it will readily float and so reach its seating if the bottle be inverted and an attempt be made to insert liquid into the bottle by suction due to a partial vacuum formed inside the said bottle. Suspended from the said float-valve by a flexible connection is a hollow weight, the said flexible connection extending from the bottom of the said weight to the bottom of the said valve. By connecting the weight to the valve at or near a point at the bottom of said weight I insure that the said valve will readily leave its seating when the bottle is inclined into a position to pour out the contents without requiring the bottle to be shaken or otherwise manipulated to cause the valve to effectually open. The float-valve and its weight are mounted in a tube having lateral passages therein and furnished with means for supporting it in the neck of a bottle. The aforesaid plug or baffle is made hollow, and in addition to having circuitous passages in its exterior surface it is provided with lateral passages leading from the interior to the exterior thereof, so that ample space is provided for the entrance of air and egress of liquid from the bottle when the contents are being poured out.

In order that my said invention may be clearly understood and readily carried into effect, I will describe the same more fully, with

reference to the accompanying drawings, in which—

Figures 1 and 2 are vertical sections of a bottle provided with my improved device, consisting of the float-valve, the tube with lateral orifices, the hollow weight, and the hollow baffle with lateral passages, Fig. 1 representing the bottle in its upright position and Fig. 2 representing it in its tilted position for pouring out the contents. Fig. 3 is an elevation of the plug or baffle detached from the bottle. Fig. 4 is a cross-section of the weight suspended from the float-valve, the said section being taken on the line 1 1 of Fig. 2.

a is the bottle, having the interior of its neck *b* slightly tapered toward the point of junction with the body of the bottle.

c is the tube for supporting the valve and its weight, said tube being enlarged or flanged at its upper end *d* to form a seating for the valve. *e* are the lateral holes in said tube. *f* is a ring of cork or other resilient material which surrounds the upper end of said tube *c* and by means of which said tube is firmly retained in position within the neck of the bottle.

g is the valve, and *i* is the weight connected therewith by the flexible connection *h*. The said valve is formed with a pointed head *g'*, which may be made plain, as represented in the drawings, or be formed with longitudinal ridges thereon. The valve, whether made with ridges or plain, must be made of sufficient buoyancy to insure its floating in pure spirits. By providing the valve with the said head the incoming air entering the bottle when the contents are being poured out will, as already stated, not be liable to cause the valve to return to its seating, as would otherwise be the case if said head were of more or less flattened form. The weight *i* is made hollow and has an opening at its upper end *i'* and at its lower end *i''*, so that the liquid contents of the bottle can freely enter said weight.

j is a transverse piece extending across the opening *i''* at the bottom of the weight to enable the flexible connection *h* to be readily connected to the bottom of said weight. The weight is preferably made of conical or pear shape, slightly flattened on opposite sides, as

represented in Fig. 4, so that when the bottle is tilted into the critical position—*i. e.*, the position that allows the weight to fall forward against the tube *c*—the float-valve is released and leaves its seating. (See Fig. 2.) When the said weight comes against the tube *c*, it will not close the latter, but will leave spaces *c' c'* for the liquid to flow past said weight into the tube or for the air to ascend into the air-chamber of the bottle. I do not wish to confine myself to the conical or pear shape of the said weight, as it may be made of any other suitable form.

A is the plug or baffle, which is located just above the float-valve in the neck of the bottle for the purpose of preventing said valve from being fraudulently operated by a wire or other instrument. Said plug or baffle is made with a cavity *A'* and has several lateral passages *A²* extending from said cavity to the exterior of the plug or baffle. It is also formed with annular grooves *A³ A⁴*, which communicate with each other by several vertical passages or V-shaped notches *A⁵* and with the space beneath said plug or baffle by several vertical passages or V-shaped notches *A⁶*. By providing the internal cavity *A'* and the lateral passages *A²* in addition to the aforesaid annular grooves and vertical passages I provide for an increased outflow of liquid and inflow of air from and to the bottle when the contents are being poured out. Moreover, the said cavity *A'* in the plug or baffle permits the pointed head of the float-valve to enter said plug, so that when the valve leaves its seating it may be supported by the wall of the hollow plug and be prevented from becoming too much displaced from its seating and from becoming locked in its open position by engaging at an angle with the mouth of the tube *c* or by engaging with other parts of the device within its reach.

What I claim, and desire to secure by Letters Patent of the United States, is—

45 1. In a non-refillable bottle, the combination of a hollow float-valve having a pointed upper part and a semispherical self-seating lower part, of a tube entirely open at both ends and formed at its upper end with a seat for said valve, and a weight suspended from said valve by a flexible connection extending from the lower end of the weight to the lower end of the valve, substantially as and for the purpose specified.

55 2. In a non-refillable bottle, the combination of a hollow float-valve having a pointed upper part and a semispherical self-seating lower part, of a tube entirely open at both ends and formed at its upper end with a seat for said valve, a hollow conically-shaped weight, open

to the liquid contents of the bottle and connected to the valve by a flexible connection extending from the lower end of the weight to the lower end of the valve, substantially as and for the purpose specified. 65

3. In a non-refillable bottle, the combination of a hollow float-valve having a pointed upper part and a semispherical self-seating lower part, of a tube entirely open at both ends and formed at its upper end with a seat for said valve, a hollow conically-shaped weight connected to the valve by a flexible connection extending from the lower end of the weight to the lower end of the valve, the said weight being open at both ends to the liquid in the bottle, and being in cross-section of different shape to that of the said tube so as to leave spaces between the sides of the weight and the lower end of the tube when the weight comes against the end of said tube, substantially as and for the purpose specified. 75

4. In a non-refillable bottle, the combination of a hollow float-valve having a ridged pointed upper part and a semispherical self-seating lower part, of a tube entirely open at both ends and formed at its upper end with a seat for said valve, and provided at its sides, approximately midway of its length, with lateral holes, a hollow conically-shaped weight connected to the valve by a flexible connection extending from the lower end of the weight to the lower end of the valve, the said weight being open at both ends to the liquid in the bottle and having its opposite sides flattened, substantially as and for the purpose specified. 80

5. In a non-refillable bottle, the combination with an open-ended tube fitted in the neck of the bottle and provided with lateral openings, of a hollow float-valve having a pointed upper end and a semispherical lower portion arranged to seat in and close the upper end of said tube, a hollow open-ended weight suspended from the valve and arranged to seat in the lower end of the tube 105 when the bottle is inverted, and a hollow plug fitted in the bottle-neck above the valve, said plug being provided with a series of lateral openings and a plurality of circumferential grooves, the grooves being connected one with the other by grooves or notches, substantially as shown and described. 110

In testimony whereof I have hereunto set my hand, in presence of two subscribing witnesses, this 19th day of January, 1900.

ARTHUR CHARLES CAVENDISH LIARDET.
